UNITED STATES PATENT OFFICE.

JULIUS F. ADAMS, OF PITTSBURGH, PENNSYLVANIA.

DESIGN FOR A GAS HEATER.

Application filed October 31, 1921. Serial No. 511,940. Term of patent 7 years.

To all whom it may concern:

Be it known that I, JULIUS F. ADAMS, a citizen of the United States, residing at Pittsburgh, in the county of Allegheny and State of Pennsylvania, have invented a new, original, and ornamental Design for Gas Heaters, of which the following is a specification, reference being had to the accompanying drawing, forming part thereof.

The figure represents a front view of a gas heater showing my new design.

I claim:

The ornamental design for a gas heater, as shown.

JULIUS F. ADAMS.
